PRESSURE RESPONSIVE MERCURY SWITCH

Winifred J. Turnupseed, Porterville, and Harley
E. Turnupseed, Tulare, Calif.

Application June 20, 1950, Serial No. 169,106

4 Claims. (Cl. 200—83)

1

This invention relates to the class of electrical switches, and particularly to a time delay switch using a fluid conductor such as mercury for closing a pair of electrical contacts to complete an electrical circuit.

An object of this invention is to provide a switch having a container for a fluid conductor such as mercury therein, which container is provided with a baffle for determining the time necessary for the passage of the fluid conductor from one portion of the switch to another so as to control the time between the actuation of the switch and the closing of a pair of electrical contacts located therein, and to further control the time between the de-activation of the switch and the time at which the fluid conductor will pass to a chamber opposed to the chamber where the contacts are in so as to open the circuits between the contacts.

A further object of this invention is to provide pressure actuated means for actuating the mercury switch which include a spring pressed link mechanism, operatively secured to a pressure responsive diaphragm and to the container of the fluid conductor.

Still further objects of the invention reside in the provision of a mercury switch that is strong, durable, highly efficient in operation, simple in construction and manufacture, flow acting, relatively easy to manufacture having the ability to be manufactured in different sizes that at given ranges of time delay, and which mercury switch is comparatively inexpensive.

These, together with various ancillary objects of the invention which will become apparent as the following description proceeds, are attained by this mercury switch, a preferred embodiment of which has been illustrated in the accompanying drawings, by way of example, wherein:

Figure 1 is a side view with parts being shown in section of the mercury switch in a position with the mercury tube at rest with the fluid conductor in such position as to permit an open circuit between the contacts in the switch;

Figure 2 is a side elevational view with parts being shown in section to show the invention more clearly, and with the mercury tube in an at rest position with the contacts closed;

Figure 3 is a vertical sectional view as taken along line 3—3 in Figure 1;

Figure 4 is a vertical sectional view taken along line 4—4 in Figure 1; and

Figure 5 is a perspective view of the baffle which is secured in the container for the liquid and which comprises one element of the present invention.

With continuing reference to the accompanying drawings wherein like reference numerals designate similar parts throughout the various views, reference numeral 10 generally designates

5 a housing in which a pressure responsive diaphragm 12 is mounted. The diaphragm is controlled by the pressure applied through the conduit 14 operatively connected thereto. Pivottally connected to the diaphragm is a rod 16 which is threaded as at 18 and which passes through the housing 10. By means of nut 20 and spring 22 the amount of movement of the diaphragm 12 relative to the pressure applied through the conduit 14 can be adjustably controlled.

10 By means of a bracket 24 there is pivotally mounted and connected to the diaphragm 12 an arm 26 which has rotatably mounted thereon a roller 28. Also mounted on the housing 10 by suitable rivets or bolts 30 is a bracket 32 to which a substantially L-shaped worker arm 34 is pivotally attached by a pivot pin 35. The worker arm 34 is riveted or otherwise attached to a clamp like member 36 which encompasses and rigidly holds a container portion 38 of a fluid conductor or mercury switch having a pair of spaced contacts 40 and 42.

15 The clamp 36 consists of two portions 44 and 46 which by means of bolt 48 and nut 50 are held together in an embracing relationship about the container 38. A coiled spring 52 is terminally secured to the arm 26 and to the bracket 32 and continuously urges the roller 28 into engagement with the beveled end 54 of the worker arm 34. Another tension spring 56 is terminally secured to the worker arm 34 and to the bracket 32 for continuously urging the worker arm downwardly and selectively urging the worker arm 34 into engagement with the roller 28.

20 The contacts 42 and 40 extend through the end wall 58 which is formed from a suitable insulative material. The container 38 is filled with a suitable fluid conductor such as mercury 60 and has a baffle or partition 62 secured therein thus effectively dividing the container into two compartments. There is provided an aperture 64 in the baffle 62 for effectuating a passageway for the mercury 60 through the baffle. An opening 66 in the baffle is provided for the passage of air to compensate for the flow of the fluid conductor. The operation of this time delayed action mercury switch is as follows:

25 When the pressure from the pressure conduit 14 is applied at its critical amount, the mercury tube is at rest with the arm 34 positioned by the transverse stop pin 70 engaging the edge of the bracket 32 under the influence of the spring 56 as shown in Figure 2. When the pressure in the conduit 14 is reduced below this critical point, the diaphragm arm 26 will move downward with the roller 28 engaging the point 54 of the arm 34. After the roller 28 passes the dead center of the end 54 of the worker arm 34, the worker arm 34 changes its position very quickly moving the mercury tube to the raised position 30 with the heel 72 of the arm 34 in contact with the

stop 14 limiting the upward movement of the point 54 as shown in Figure 1. The contact end of the mercury tube is raised and the mercury passes through the opening 64 at a substantially slow rate thus permitting the circuit between the contacts 40 and 42 to remain closed for a suitable delay until enough mercury passes into the opposite portion of the container 38 thus opening the circuit.

When pressure in the line 14 again achieves the critical pressure, the pivoted arm 26 moves upwardly and when the pivoted roller passes the dead center line as before the worker arm is actuated so as to return the mercury tube to back its normal position as shown in Figure 2. The mercury passes slowly back through the aperture 64 and after a suitable delay closes the circuit between the contacts 40 and 42.

It is to be understood that this particular type of mercury switch can be changed to operate many time-given ranges of time-delay, by changing the size of the hole 64, by changing the size of the baffle 62, by changing the size of the mercury tube 38, by increasing the amount of mercury or by suitably positioning of the contacts 40 and 42.

It is to be further understood that this type of mercury switch can operate through open contacts at high pressure and to close the contacts at low pressure or vice versa.

Since from the foregoing the construction and advantages of this mercury switch are readily apparent and further description is believed to be unnecessary.

However, since numerous modifications will readily occur to those skilled in the art, it is not intended to limit the invention to the precise embodiment shown and described but all suitable modifications and equivalents may be readily resorted to which fall within the scope 40 of the appended claims.

Having described the invention, what is claimed as new is:

1. In a pressure responsive switch assembly having a tiltable container partially filled with mercury, a pair of contacts in said container adapted to be closed by the mercury in one position of the switch, and a baffle wall in said container provided with a passageway for producing a delayed operation, a pressure responsive means for tilting said container, comprising a pressure responsive diaphragm, and means for completely tilting the mercury switch when the pressure responsive diaphragm is moved to a predetermined extent, said last named means including a member pivotally mounted on said diaphragm and responsive to the movement of the diaphragm, a roller rotatably secured on said member, a worker arm attached to said container and provided with a pointed end, and means to maintain engagement between said worker arm and said roller for tilting said container completely as soon as the pointed end of the worker arm passes from one side of the roller to the other side during the movement of the diaphragm.

2. For use in a pressure responsive mercury switch assembly having a mercury switch provided with a container partially filled with mercury and a pair of circuit controlling contacts closed by the mercury when the switch is tilted, a baffle wall in said container provided with a mercury passageway and a vent aperture for delaying the flow of mercury within the container, thereby producing a time delay between 75

a tilting of the container and the closing of the contact, means for tilting said container completely in response to pressure variation exceeding a predetermined value, said means comprising a pressure responsive diaphragm, an arm pivotally connected with said diaphragm and performing a movement proportional to the diaphragm movement, said arm carrying a roller rotatably secured to the same, a housing for the pressure responsive device, a worker arm of substantially L-shape pivotally secured to the housing, said worker arm being rigidly connected to said container, and being adapted to engage said roller, means continuously urging said roller into engagement with said worker arm and other means selectively urging said worker arm into engagement with said roller, and means operatively connected to said diaphragm and said housing for adjusting the movement of the diaphragm for controlling the pressure at which said diaphragm is moved to the extent required for the actuation of said mercury switch.

3. For use with a tilting type switch, a pressure responsive tilting mechanism comprising: 25 a housing, a pressure responsive diaphragm mounted in said housing, an arm pivotally attached to said diaphragm, said housing having a slot therein, said arm extending through said slot, an upstanding bracket mounted on said housing, a working arm mounted for limited pivotal movement on said bracket, means biasing said working arm into one position, a clamp on said arm adapted to support a switch means on said arm, means biasing said first mentioned arm toward said bracket, a roller journaled on said first mentioned arm, a beveled end on said working arm, said roller engaging said beveled end to determine the position of said working arm.

4. For use with a tilting type switch, a pressure responsive tilting mechanism comprising: a housing, a pressure responsive diaphragm mounted in said housing, an arm pivotally attached to said diaphragm, said housing having a slot therein, said arm extending through said slot, an upstanding bracket mounted on said housing, a working arm mounted for limited pivotal movement on said bracket, means biasing said working arm into one position, a clamp on said arm adapted to support a switch means on said arm, means biasing said first mentioned arm toward said bracket, a roller journaled on said first mentioned arm, a beveled end on said working arm, said roller engaging said beveled end to determine the position of said working arm, biasing means yieldingly urging said diaphragm in one direction.
